UNITED STATES PATENT OFFICE

NORMAN L. DALRYMPLE, OF DANVILLE, VIRGINIA.

VANITY CASE.

Application filed August 31, 1923. Serial No. 660,452.

To all whom it may concern:

Be it known that I, NORMAN L. DALRYMPLE, a citizen of the United States, residing at Danville, in the county of Pittsylvania and State of Virginia, have invented certain new and useful Improvements in Vanity Cases, of which the following is a specification.

My invention has for its object to provide 10 a certain new and useful vanity case of an ornamental appearance, compact structure, and one in which the parts are so designed and correlated as to afford the greatest facility of manipulation in using the same.

15 In its more subordinate nature the invention has for its object to provide the vanity case embodying in its structure a card holder, a coin carrier, and a powder compact and puff with a mirror cooperating with the same, so arranged and designed that the parts composing the case may be opened and handled in a convenient manner and in which the parts are so constructed as to be of an ornamental appearance as well as possessing 25 utility.

30 In its general nature the invention comprises a case composed of two half sections hinged together along one edge, one of the half sections functioning as a coin carrier and a powder compact, puff and mirror carrier while the other section functions as a card carrier and as a cover for the coin holders of the first section; the section carrying the coin holders and powder cup being provided with a hinge cover that carries the 35 mirror and serves as a closure for the powder cup, the cover being hinged to that section, preferably, at the end of the case opposite the hinge joint between the two half 40 sections.

45 In its more detailed nature the invention includes those novel details of construction, combination and arrangement of parts, all of which will be first fully described, then be specifically pointed out in the appended claims, reference being had to the accompanying drawings, in which—

50 Figure 1 is a perspective view of the case looking at it from the powder compact side, the cover with the mirror being open.

55 Figure 2 is a perspective view of the case, the two half sections being opened apart and showing the location of the coin holder and the card carrying space.

55 Figure 3 is a longitudinal section of the case, the parts being in the closed position.

Figures 4 and 5 are cross sections on the lines 4—4 and 5—5 respectively of Figure 3.

In the drawing in which like numerals of reference indicate like parts in all the figures, it will be observed that the case is made of two half sections 1 and 2 hinged together at 3 and held together by a catch 4.

The section 2 has a face plate 5, which is apertured at 6 and 7 to receive a pair of coin holders 8 and 9, the coin holders being suitably secured to the plate 5 in any suitable way. The outer face of the section 2 has an opening with a rest flange 10 for the lid 11. The lid is hinged at 12 to the end of 65 the section 2 which is opposite that having the hinge 3 and it has a suitable catch 13 to hold it closed. The lid also carries a suitable mirror 14 as shown.

70 15 is a partition plate which is held in the section at such a distance from the opening as will permit the lid 11, with the mirror 14, to close down. Set into the opening 16 of the plate 15 is a cup 17 which contains a powder compact 18 and a powder puff 19, 75 the mirror 14 forming a closure for the cup 17 when the lid is down.

80 The coin holders 8 and 9 are set into the openings 6 and 7 from the outer side of the plate 5 and are secured in position in any suitable way. Plungers 21 are provided in the cup and springs 20 are set between the plungers 21 and the partition plate 15 to operate the plungers and hold the coins in proper relation with the outlet slot or opening 85 of the coin holders.

90 The section 1 of the case has its opening facing the section 2 and it is provided with a spring held clip 22 for retaining cards in place whereby the section 1 will constitute a card case as well as serving as a cover over the coin holders. 23 designates rings secured to the end of the case to which a carrying chain (not shown) may be attached.

95 From the foregoing description, taken 100 in connection with the accompanying drawing, it is thought the complete construction, uses and advantages of my invention will be clear to those skilled in the art.

105 By arranging the hinges 3 and 12 at opposite ends of the case the use of the case is greatly facilitated since the end of the case having the rings 23 may always be held up, a thing that is of considerable advantage when the case is hung from a carrying chain.

110 While the holders 8 and 9 are primarily intended to receive coin disks, it is obvious

that they may be used to contain disks of cosmetic wafers and while the compartment containing the clip 22 is primarily intended to receive cards, it may also be used to 5 contain packages of powder papers, or a piece of chamois skin, if desired.

What I claim is:

1. A case of the character described comprising a pair of half sections hinged together at one end, a catch located at the other end for holding said sections together, one of said sections constituting a receptacle and the other having an opening at the outer face thereof, a lid hinged to said other 10 section for closing said opening, and a powder cup with said other section and closed by said lid, disk holders carried by said other section with their open ends projecting into the first section when the case is 15 closed.
2. A case of the character described comprising half sections hinged together along one edge, a catch securing the sections together at the opposite edge, one of said half 20 sections having an opening in its outer wall, a lid hinged to said section for closing said opening, a partition plate carried in said section and spaced from said opening, said partition plate having an opening, a powder 25 cup with compact and puff set into said opening and closable by said lid; and a mirror carried by said lid, the hinge of said lid lying at the opposite end of the case from 30 that containing the hinge of the half sections.
3. A case of the character described comprising half sections hinged together along one edge, a catch securing the sections together at the opposite edge, one of said sections having an opening in its outer wall, a lid hinged to said section for closing said opening, a partition plate carried in said section and spaced from said opening, said partition plate having an opening, a powder 35 cup with compact and puff set into said opening and closable by said lid, and a mirror carried by said lid, one hinged section having a face plate registering with the other hinged section, said face plate having 40 an opening, a disk holder set into said face plate opening with its outlet end projected into the opposite section when closed.
4. A case of the character described comprising half sections hinged together along 45 one edge, a catch securing the sections together at the opposite edge, one of said half sections having an opening in its outer wall, a lid hinged to said section for closing said opening, a partition plate carried in said section and spaced from said opening, said partition plate having an opening, a powder cup with compact and puff set into said opening and closable by said lid, and a mirror carried by said lid, one hinged sec-

tion having a face plate registering with the other hinged section, said face plate having an opening, a disk holder set into said face plate opening with its outlet end projected into the opposite section when closed, said opposite section having a space 70 serving as a container and the said opposite section also serving as a cover over said disk holder.

5. A case of the character described, comprising a pair of half sections, each of said half sections having a face plate, the face plate of one section adapted to lie in contact with the face plate of the other section when said sections are closed, one of said face plates having an opening to give access 75 to the interior of the section, the section having the other face plate having an opening at the outer face thereof, a lid hinged to said last mentioned section to lie flush with the outer face thereof and close the opening of said section to which said lid is hinged, a powder cup within the section having the lid, said half sections being hinged together along one end, and a catch 80 located at the other end for holding said sections together, substantially as shown and described.

6. A case of the character described, comprising a pair of half sections hinged together at one end, each of said sections having an opposing face plate, the face plate of one section having a portion removed to give access to the interior of said section, a holder clip mounted in the interior of said section, disk holders mounted in the section not having the clip and projecting through the face plate of the section to a distance less than the depth of the opposing section whereby when said sections are closed said disk holder will project a short distance 100 into the section which has the clip and be spaced from the wall of said section which has the clip, and a catch for holding the said sections in the closed position.

7. A vanity case comprising a pair of half sections hinged together, each of said sections having an opposing face plate, the face plate of one section having an opening to permit access to its section when the sections are separated, the other section having an opening in its outer face, and a flush lid hinged to said other section to fit into said opening thereof and close the same, said lid lying with its outer surface flush with the outer surface of the section to which it is attached, said other section having a partition plate recessed to form a powder cup, said powder cup being closable by said lid, said lid having a mirror on its inner face to lie against said partition plate and close 115 over said powder cup, all being arranged substantially as shown and described.

NORMAN L. DALRYMPLE.
